[57] **CLAIM**

The ornamental design for a combined double gems and coil spring for fingers, as shown and described.

DESCRIPTION

FIG. 1 is a perspective top view of a combined double gems and coil spring for fingers, showing my new design; FIG. 2 is a top plan view thereof; FIG. 3 is a bottom plan view thereof; FIG. 4 is a front elevational view thereof, the rear elevational view being practically identical therewith; FIG. 5 is a left side elevational view thereof, the right side elevational view being practically identical therewith; FIG. 6 is a longitudinal cross sectional view thereof, taking along lines 6-6 of FIG. 4; and, FIG. 7 is a top plan view position of use thereof, a hand being shown in broken lines for illustrative purposes.
